UNITED STATES PATENT OFFICE.

HENRY C. THOMSON, OF BOSTON, MASSACHUSETTS, ASSIGNOR TO THE ELECTRIC GAS LIGHTING COMPANY, OF SAME PLACE.

ELECTRIC HAND-LIGHTING GAS-BURNER.

SPECIFICATION forming part of Letters Patent No. 618,920, dated February 7, 1899.

Application filed May 31, 1898. Serial No. 682,126. (No model.)

To all whom it may concern:

Be it known that I, HENRY C. THOMSON, of Boston, Massachusetts, have invented a new and useful Improvement in Electric Hand-Lighting Gas-Burners, of which the following is a specification.

My invention relates to that class of electric gas-lighting burners in which the gas-valve is opened and the vibrating electrode simultaneously operated.

My improvement consists in reconstructing and rearranging the parts of such a burner as is shown in Letters Patent No. 562,891, of June 30, 1896, to G. J. Galbraith, in such manner as to produce a new combination resulting in not only a greater simplicity of construction, but also avoiding the projection of the flexible spring-electrode in such manner as to expose it to injury or make it inconvenient in dusting or cleansing such apparatus.

My invention will be clearly understood from the following drawings, in which similar letters and numerals refer to similar parts, and in which—

25 Figure 1 is a front elevation with the gas turned off. Fig. 2 is a side elevation with the gas turned off. Figs. 3, 4, and 5 are views showing the movable electrode and its controlling parts in different positions.

30 I will now describe the drawings.

A is the ordinary burner-pillar.

A' is the fixed electrode, which may be supported in a collar 1 and which is composed of the coiled spring a, one of whose ends is fixed 35 in said collar and whose other end a² constitutes the flexible electrode-point, within which coiled spring is the pin a³, held in place by resting upon the ratchets c.

30 The movable electrode b forms the tip of the vibrating plate-arm B, its plate part being rigidly mounted upon the gas-valve E. This gas-valve is the ordinary conical rotating valve having a passage-way, which upon its rotation is coincident with the gasway 45 through the burner. The stem part of the thumb-piece D fits into a plate-piece d², (below the main-burner support or bracket,) in which is cut a cam d³, which plays against the stop 2, so as to admit of a one-quarter rotation of the thumb-cock, and said stem, then

extending through said bracket, also fits into a second plate-piece d, which is provided with teeth d'. Extending from the plate part of B are the teeth b², which gear with corresponding teeth d' upon the plate d, rigidly attached to the spindle of the handle D, so that the quarter-rotation of the handle D, secured by means of a cam d³ in the plate-piece d² and stop 2, will bring the tip b of the movable plate-arm B into and out of contact with the stationary flexible electrode a².

The whole stationary electrode A' is elevated in order to make contact with b by means of a ratchet-wheel C, loosely journaled on the extension of the gas-valve and moving 65 always from left to right—that is, in the direction of the hands of a watch. As the ratchets c pass under the pin a³ the said pin causes an extension of the coiled spring a, and so permits of the making and breaking 70 of the contact between a² and b.

To secure the continuous rotation of the ratchet-wheel C, the clutch F is attached to the plate part of B, so that the ratchet-wheel is caused to revolve in turning the gas on; 75 but in turning it off the end of the clutch slides over the ratchet-teeth c, the ratchet-wheel being prevented from revolving in the contrary direction by the pin a³, serving as a 80 detent.

Having described my improvement, I do not claim any of the elements themselves as novel; but

What I wish to protect by Letters Patent and claim is—

1. In an electric hand-lighting gas-burner, in combination with the ordinary burner-pillar, a fixed electrode consisting of a coiled spring, properly attached to the burner-pillar and terminating in an electrode-point, and a pin within the said coiled spring; a ratchet-wheel loosely journaled upon the gas-cock stem and supporting said electrode-pin; a plate-piece rigidly fixed to the gas-cock stem, having its upper arm adapted as a movable electrode and having teeth upon its lower plate edge; a spring-clutch rigidly attached to said plate-arm to move said ratchet-wheel; a thumb piece or key carrying a plate having teeth adapted to gear with the teeth upon the 100

bottom of the plate-piece; substantially as described and shown.

2. An electric hand-lighting gas-burner composed of the gas-pillar A; a vertically-movable electrode consisting of a coiled spring a and pin a³ within the same; a rotating gas-cock E having a projecting spindle; a ratchet-wheel C loosely journaled upon said spindle; a vibrating plate-arm B having the electrode b and the teeth b²; a clutch F fixed to said plate-piece B; a handle D; a plate-piece d

having the teeth d' carried by said handle; and a plate d², also carried by said handle and having a cam d³ to limit the movement of the handle-piece to a one-quarter movement; substantially as described and shown. 15

In witness whereof I hereunto sign my name this 30th day of April, A. D. 1898.

HENRY C. THOMSON.
